UNITED STATES PATENT OFFICE

129,424

DESIGN FOR A TEXTILE FABRIC

Herman E. Goodman, New York, N. Y.

Application May 8, 1941, Serial No. 100,843

Term of patent 3½ years

To whom it may concern:

Be it known that I, Herman E. Goodman, a citizen of the United States, residing at Manhattan, county of New York and State of New York, have invented a new, original, and ornamental Design for a Textile Fabric, of which the following is a specification, reference being had to the accompanying drawings, forming part thereof, wherein

I claim:

The ornamental design for a textile fabric, substantially as shown and described.

HERMAN E. GOODMAN.
